J. A. WOLCOTT.

CONCENTRATOR.

APPLICATION FILED DEO. 16, 1912

1,071,492.

Patented Aug. 26, 1913.

UNITED STATES PATENT OFFICE.

JOHN A. WOLCOTT, OF BANDON, OREGON.

CONCENTRATOR.

1,071,492.

Specification of Letters Patent. Patented Aug. 26, 1913.

Application filed December 16, 1912. Serial No. 737,067.

To all whom it may concern:

Be it known that I, JOHN A. WOLCOTT, a citizen of the United States, residing at Bandon, in the county of Coos and State of Oregon, have invented a new and useful Concentrator, of which the following is a specification.

The present invention relates to improvements in concentrators, the same being designed for special use in concentrating precious metals from black sand and the like, one object of the invention being the provision of a concentrating sluice way or trough mounted for transverse oscillatory movement and having disposed therein, a plurality of independently reciprocatory paddles, both the paddles and the trough being operated simultaneously so that the water containing the gangue and the precious metal will be continually agitated to cause the heavier particles to be precipitated for removal from the sluice way or trough.

A further object of the present invention is the provision of a novel mechanism whereby a plurality of longitudinally disposed and reciprocatory members carrying pivoted stirring paddles will have the necessary reciprocatory movement imparted thereto.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—Figure 1 is a side elevation of the complete device taken from the power side thereof. Fig. 2 is a longitudinal sectional view therethrough. Fig. 3 is a side elevation taken from the opposite side to the power mechanism. Fig. 4 is a section taken on line 4—4 of Fig. 3. Fig. 5 is a detail view illustrating the paddle mounting.

Referring to the drawings, the numeral 1 designates the base of the machine which has connected thereto, and upstanding therefrom, the two forward vertical posts 2 and the two rear vertical posts 2', while

connected to the base adjacent the respective pairs of posts are the cross bars 3—3' respectively. Connected to the upper face of the bars 3—3' upon the power side of the machine is a pair of journaling straps 4 for the reception of the lower terminals of the two trough or table supporting bails 5, the upper ends of said bails being pivotally connected by straps 6 to the under side of the trough or table 7. This trough or table 65 is preferably made of sheet metal and has its bottom 7' formed as clearly shown in Fig. 2, the straps 5 forming a means to support the trough at one side and at the same time permit of the necessary and desirable transverse oscillatory movement between the vertical posts 2—2'. 70

A shaft 8 is journaled in the straps 9—9' carried by the respective bars 3—3' and fixed to this shaft and upstanding therefrom 75 are the two crank shafts 10—10', each one of which is properly mounted within the straps 11—11' connected to the lower portion of the trough 7 at the opposite side to the straps 6. Thus the bails or arms 5 contact with the cranks 10—10' to properly support the trough 7 between the respective pairs of posts 2—2'. 80

The shaft 8 is the medium through which the trough or table 7 is transversely oscillated between the pairs of posts and in order to accomplish this, a crank arm 12 is provided at one end of the shaft 9 and projects outwardly beyond one of the posts 2, its outer end being connected to the lower 90 end of the strap 13, whose upper end is removably connected to the short crank arm 14 keyed upon and rotatable with the shaft 15. This shaft 15 is journaled in the bracket 16 which is mounted upon the forward two posts 2 the shaft 15 being transversely of and below the trough 7. The driving sprocket 17 is keyed upon the shaft 15 at the opposite end to the crank 14 and has trained thereover, a sprocket chain 18, by 100 means of which the shaft 15 is rotated to impart the necessary oscillatory movement to the shaft 8. 95

Connected to the forward portions near the upper ends of the posts 2—2', are the blocks 19 which carry, the brackets 20 for the reception of the transversely disposed shaft 21. This shaft 21 has keyed upon the end above the sprocket 17, a large sprocket 100, which has trained thereover, the 110

sprocket chain 18, so that both shafts 21 and 15 may be rotated simultaneously and from the same power mechanism.

Disposed for longitudinal reciprocatory movement above the trough or table 7 are a plurality of stirring members 22, each one of which is provided with the longitudinal and parallel flanges or rims 23 and at their forward ends with the elongated slots 24, there being one slot 24 to each member 22.

In order to properly support each stirring member 22 so that it may maintain the same relative position to the posts 2-2' at all times, an arm 25 having the securing end 26 attached to the upper surface of the stirring member between the posts 2, is provided, the free end of said arm being disposed for sliding movement upon the shaft 21. Thus the arm 25 and the shaft 21 provide a means for retaining one of the stirring members 22 properly positioned. Connected at 28 to each stirring member adjacent to the two posts 2' is an arm 27, the free end of said arm being inserted 25 through its respective eye 29 of the rod 30 which is fastened by means of the eye bolts 31 to the posts 2'. Thus the rod is properly positioned transversely of and above the trough or table 7 and with the shaft 21 and

30 the respective arms 25 and 27 provide a means for properly supporting the reciprocatory stirring members 22 so that the swingingly mounted paddles 33 carried by the respective stirring members 22 and journaled upon the pins 32 between the flanges 23 thereof are properly positioned within the trough or table so that as the trough is moved transversely and the stirring members 22 are moved longitudinally, each one of

35 their respective paddles 33 produces the necessary stirring motion to the contents of the trough to assist in the precipitation of the heavier particles upon the bottom 7' and upon the inclined portion 36, where the 40 heavier particles will enter and pass through the outlet ports or apertures 37 at the closed end of the trough or table. These paddles 33 are so disposed, as shown in Fig. 5, that when moved to the right as viewed in Fig.

45 2, that the resistance of the material and water within the trough will cause the same to move to the left to finally be limited in such movement to resist the material and stir the same, the movement of the members 50 22 to the left as viewed in Fig. 2, causing the paddles to swing upwardly toward the stirring members 22 and reduce the stirring action, so that the lighter particles will be gradually moved from the left to the right 55 60 as viewed in Fig. 2 and finally out of the open end of the trough or table.

In order that the shaft 21 may impart the necessary reciprocatory movement to the respective stirring members 22 and their paddles 33, a ring 34 provided with the secur-

ing apertured lug 35 is connected to the shaft 21 and is projected through the slot 24 of its respective member 22, and as said ring 34 is thus connected eccentrically to the shaft 21, the rotation of the shaft will cause the ring 34 in its engagement with the walls of the slot 24 of the member 22 to thus push and pull the member 22 and move the same longitudinally of the apparatus. The respective rings 34, there being three in the present instance are connected to the shaft 21, at different angles, so that the members 22 are moved successively in different directions so as to continue the stirring action of the material within the trough or table and thus materially assist in the precipitation of the precious metal and its final delivery through the apertures 37. As the arms 25 are preferably made bail-shaped, and as the open portion thereof is vertically above and aligned with the slot 24, the ring 34 not only fits in the slot 24 of the member 22 but also moves upward in the open portion of the arm 25 and thus the arm 25 coacts with the aperture 24 in assisting the ring 34 to impart the necessary reciprocatory movement to the member 22.

What is claimed is:

1. A concentrator, including a base, two pairs of uprights carried by the base adjacent the respective ends thereof, a trough disposed between said uprights, means for pivotally connecting and supporting the trough from the base between the uprights, means for actuating said supporting means to impart a transverse oscillatory movement to the trough, two shafts, one mounted in each pair of uprights and above the trough, a plurality of longitudinal stirring members, means carried by said members and coacting with the shafts for retaining the members above the trough and permitting a reciprocatory movement to the members, and means mounted upon one pair of the uprights for imparting a reciprocatory movement to the members.

2. A concentrator, including a base, two pairs of uprights carried by the base, a trough mounted between said uprights and for transverse oscillatory movement, a shaft journaled in two of the uprights above and transversely of the trough, a rod connected to the other two uprights and transversely of and above the trough at the opposite end, a plurality of stirring members, two arms carried by each stirring member one to the shaft and one to the rod for coaction therewith to support the stirring member above the trough, and coöperable means carried by the shaft and the stirring member for imparting reciprocatory movement to the stirring member during the rotation of the shaft.

3. A concentrator, including a base, two pairs of uprights carried by the base, a

- trough mounted between said uprights and for transverse oscillatory movement, a shaft journaled in two of the uprights above and transversely of the trough, a rod connected 5 to the other two uprights and transversely of and above the trough at the opposite end, a plurality of stirring members, two arms carried by each stirring member one to the shaft and one to the rod for coaction there- 10 with to support the stirring member above the trough, the end of the stirring members adjacent to the shaft being slotted, and a plurality of eccentrics, one to each stirring member keyed upon and rotatable with the 15 shaft and for projection within the slot of the stirring member, whereby the rotation of the shaft will impart a reciprocatory movement to the stirring members.
4. A concentrator, including a base, two 20 pairs of uprights carried by the base, a trough mounted between the uprights, a rod connected to one pair of uprights transversely of and above the trough, a shaft journaled in the other upright transversely of 25 and above the trough, a plurality of longitudinally disposed reciprocatory plates, a plurality of swingingly mounted stirring members carried by each plate, two arms connected to each plate, one of said arms 30 being disposed to slide upon and be guided by the rod while the other arm is mounted upon the shaft, and a plurality of rings connected eccentrically to the shaft, and engageable with the reciprocatory plates, whereby the rotation of the shaft imparts a reciprocatory movement to the plates.
- In testimony that I claim the foregoing 55 as my own, I have hereto affixed my signature in the presence of two witnesses.

JOHN A. WOLCOTT.
